232,762

**TOOL HOLDER FOR END WORKING TOOLS FOR
A LATHE, OR SIMILAR ARTICLE**

Pasquale Joseph Lanese, Mayfield Heights, Ohio, assignor
to The Warner & Swasey Company, Cleveland, Ohio

Filed Sept. 11, 1972, Ser. No. 287,987

Term of patent 14 years

Int. Cl. D15—09

U.S. Cl. D54—6

FIG. 1

FIG. 2

FIG. 3

FIG. 4

FIG. 1 is a perspective view of a tool holder for end working tools for a lathe, or similar article embodying my new design and looking at the front and left-hand side of the tool holder;

FIG. 2 is a rear elevational view looking at the rear of the rear of the tool holder of FIG. 1;

FIG. 3 is a side elevational view looking at the right hand side of the tool holder of FIG. 1;

FIG. 4 is a bottom plan view of the tool holder looking at the bottom of the holder as shown in FIG. 3.

I claim:

The ornamental design for a tool holder for end working tools for a lathe, or similar article, as shown.
